No. 14,339

Oct 2, 1883

UNITED STATES PATENT OFFICE.

EMIL JANSEN, OF PATERSON, NEW JERSEY, ASSIGNOR TO THE BRUSSELS TAPESTRY COMPANY, OF NEW YORK.

DESIGN FOR A HANDKERCHIEF AND SCARF.

SPECIFICATION forming part of Design No. 14,339, dated October 2, 1883.

Application filed August 16, 1883. Term of patent 3½ years.

To all whom it may concern:

Be it known that I, EMIL JANSEN, a subject of the Emperor of Germany, residing at Paterson, in the county of Passaic and State 5 of New Jersey, have invented a new and useful Design for Handkerchiefs and Scarfs, of which the following is a specification.

The leading feature of my design is a loose bunch of moss-roses, with leaves, stalks, and 10 buds, some closed and some partially opened. Springing from the corner of an angle are main thorned stems or stalks, with several lateral branches, the side branches having at their lower portions tripartite leaves displayed 15 flat or open. Upon the upper ends of each of two of the main thorned stalks or stems, respectively, is a full-blown rose, between which two roses extend upwardly several forked branches of the main stems, and upon the ends 20 of each of four of the forked branches is a rose-bud, one of said buds being closed up, the others being more or less bursting into bloom. Said flowers and buds, with their leaves and stalks, represent a loose bunch of 25 roses budding and in bloom. The whole is displayed on a combined floral and arabesque entablature or background conforming substantially to two sides of an angle, the marginal outline of said entablature or background 30 is slightly curved inwardly, but at the corner

or apex of the entablature is a small indent or cut-away portion, exposing an open space unornamented. The entablature is wholly filled up with combined floral and arabesque figures, having on one of its arms an ornamental scalloped cross filled up in diaper pattern, and quarter-foil ornaments, and the opposite arm of the entablature has a cross-shaped leaf-piece. The interstitial spaces are filled up with small leaves, arabesque figures, dots, and connecting- 35 40 lines.

The design is intended to form corner or edge pieces for textile fabrics of any suitable configuration, and is adaptable for articles of quadrangular, circular, elliptical, or polygonal outer conformation, and can be arranged by repetition to form of itself a complete border design; but it will be entirely within the scope of my invention to connect it to side or center entablatures or suitable additional ornamental pieces. 45 50

What I claim, and desire to secure by Letters Patent, is—

The within-described floral and arabesque design for handkerchiefs and scarfs, as shown. 55

EMIL JANSEN.
